ERICH BARTELS, OF DUSSELDORF, GERMANY, ASSIGNOR TO THE FIRM OF RHEINISCHE METALLWAAREN- UND MASCHINENFABRIK, OF DUSSELDORF-DERENDORF, GERMANY

PRIMER LOCK

Application filed February 8, 1929, Serial No. 338,600, and in Germany February 20, 1928.

The construction of a primer lock with trigger, that is to say the construction of the most important and simultaneously the most sensitive portion of the breech mechanism of a gun is clearly determined by the fact, that all details must be limited in number as far as possible and must be easily exchangeable, so as to adapt the gun for services in the field. Particularly all the different elements of the primer lock must be arranged as close together as possible, so as to require for their reception the smallest possible bore in the breech mechanism, thereby effectively opposing an unnecessary reduction of the strength of the breech portion.

The object of the present invention is to provide a device which answers all purposes indicated above.

With regard to known constructions the device according to the invention is characterized by the fact, that the trigger is arranged in the plunger-like percussion hammer and by a particular formation of the latter which permits the arrangement of all members, with the exception of the trigger shaft, in a single bore of the breech block. Hereby it is possible to remove or insert the primer lock while the breech mechanism is closed which may be effected by simply disengaging the protecting cover which serves as an abutment for the main spring and is bayonet-like arranged in the breech member. Moreover such a construction obviates a particular recess in the breech member for the reception of a lock member arranged separately from the percussion hammer.

The accompanying drawing shows by way of example a device according to the invention as applied to a breech mechanism of a gun.

Figure 1 shows a part sectional view of the primer lock with the trigger in the position of rest; Figure 2 illustrates in part sectional elevation the primer lock in the position in which the trigger lever is completely tilted, that is to say the main spring is tensioned to a maximum; Figure 3 is a part sectional view of the primer lock in the released position; Figure 4 is a part sectional elevation of the device according to the invention showing

the different parts in the position they occupy at the beginning of the return movement of the lock into the position of rest after release of the trigger lever; Figure 5 is a cross section on line I—I of Figure 1 looking from the point of the percussion hammer; Figure 6 is a cross section also on line I—I of Figure 1, but looking in the direction from the butt-end of the percussion hammer; Figure 7 is a bottom plan view of the plunger; Figure 8 illustrates a top plan view of the plunger; Figure 9 shows elevation of the trigger member and Figure 10 is a view of the front spring abutment looking from the point of the percussion hammer.

The cylindrical plunger body *b* of the primer lock carries at its front face the point *b*₁ of the percussion hammer and is slidably arranged in a bore *a*₁ of the breech mechanism *a* provided in the prolongation or extension of the axis of the bore of the gun. Rotation of the longitudinally movable plunger *b* is prevented by a nose *b*₂ slidingly engaging a corresponding groove of the wedge member. A part of the plunger *b* is provided with a bore for the reception of the main spring *f*. A cover *a*₂ connected bayonet-like to the breech member serves as fixed rearward abutment for the spring *f*. The front end of the spring *f* bears against a disc *c* arranged with a certain play in the bore *b*₄ of the plunger *b*. The disc *c* carries at its lower part an eye *c*₁ snugly fitting a longitudinal slot *b*₅ of the plunger body *b*. A conical pin *d* of small diameter, arranged normally to a vertical plane passing through the axis of the percussion hammer, is extended through the hole of the eye *c*₁. Hereby it is possible to tilt the disc *c* about a certain angle rearwardly with regard to the vertical cross wall *b*₃ of the plunger body *b*. Furthermore the face of the disc *c* directed towards the point *b*₁ of the percussion hammer carries a cam *c*₃ which extends through a bore *b*₆ of the plunger body *b* and bears against the slide face *g*₁ of the trigger *g* the pivot pin *g*₂ of which is rotatably arranged in the plunger body *b*. As the main spring is inserted under a certain tension, the trigger *g* positively engages the cam *c*₃ of the disc *c*

when the parts of the primer lock are assembled. The trigger shaft pivotally arranged in the breech block *a* carries at its end extending into the bore *a*₁ a cam disc *e*. One face 5 *e*₃ of this disc *e*, in connection with the cam lever *g*₃ hinged to the trigger *g*, causes the cocking or the tensioning and the release of the primer lock when the trigger shaft is rotated. Finally, after triggering and after the 10 plunger body *b* has been suddenly moved forward, the trigger shaft is, after release of the trigger lever, rotated backwardly, whereby the cam disc *e* is also returned, so that the second cam face *e*₂ of same engages the wall 15 of the recess *b*₁₂ of the plunger body *b*, whereby this body, mostly under the influence of a torsional spring connected to the trigger shaft, is returned to its position of rest.

During the release period the cinematic 20 movements of the several parts of the primer lock are carried out in the order shown in Figures 1 to 4.

When in the so called position of rest (Figure 1) the primer lock is to cock and to release, the trigger shaft is rotated in the direction of the arrow *z* shown in Figure 1, whereby the cam disc *e*, rigidly connected to the trigger shaft, is also rotated in the same sense. As the face *e*₃ of the cam disc *e* engages 25 the finger lever *g*₃ of the trigger *g*, journalled in the plunger body *b*, the initiated torque causes a longitudinal backward movement of the plunger body *b* and therefore the cocking or tensioning of the main spring *f*. This 30 movement is continued until the shoulder surface *e*₄ of the same disc *e* coincides with the plane passing through the surface *g*₅ of the finger lever *g*₃ hinged to the trigger *g* (Figure 2). When this position is reached 35 40 the plunger body *b* is suddenly moved forward under the action of the spring *f*, whereby the point *b*₁ of the percussion hammer is brought into the priming position (Figure 3).

After firing, the point *b*₁ of the percussion 45 hammer struck into the cap of the cartridge must be redrawn behind the front face of the primer lock *a* to allow the opening of the breech member. To effect this, the trigger 50 shaft is under the action of a torsional spring not shown in the drawing by which, after release of the trigger lever, this lever and therefore the trigger shaft also are returned to the original position. When during this 55 rotational movement the trigger shaft occupies the position shown in Figure 4, the stop surface *e*₂ of the cam disc *e*, rigidly connected to the trigger shaft, bears against the wall of a recess of the plunger body *b*, whereby 60 this body and with the same the point of the percussion hammer is, until the final exit position of the trigger lever (Figure 1) is reached, forced back into the plunger body so far, that the point *b*₁ of the percussion ham- 65 mer does not longer extend into the path of

the breech mechanism in the bottom piece of the barrel. During this time the finger lever *g*₃ occupies with regard to the cam disc the position required for effecting again the pulling of the trigger. For this purpose the 70 main spring *f* is inserted with a certain tension, so that the cam *e*₂ of the front disc *e*, tilting about a certain angle around the axis of the pin *d*, positively engages the surface *g*₁ of the trigger *g*. The finger lever *g*₃, 75 rigidly connected to the trigger *g*, rolls along the surface *e*₃ of the cam disc *e* until the trigger lever or the trigger shaft occupies the original position and the finger lever *g*₃ engages behind the cam disc *e*₃ occupying there- 80 by with regard to this disc a position which again allows pulling of the trigger.

What I claim is:

1. In a primer lock for the breech mechanism of a gun, in combination a percussion hammer slideably fitting said breech mechanism, a cam disc fixed upon a spring actuated cocking shaft rotatably arranged in said breech block, a trigger journalled in said percussion hammer and cooperating with said cam disc, a spring located in a bore of said percussion hammer, a disc forming a bearing for said spring and swingably arranged in said bore and a cam on said disc cooperating with said trigger. 95

2. In a primer lock for the breech mechanism of a gun, in combination a percussion hammer slidably fitting said breech mechanism, a cam disc fixed upon a spring actuated cocking shaft rotatably arranged in said breech block, a trigger journalled in said percussion hammer, said disc having a plurality of cams some of which cooperate with an arm extending from said trigger and one of which being adapted to enter a recess of said percussion hammer, so as to allow retraction of said percussion hammer after firing, a spring located in a bore of said percussion hammer, a disc forming a bearing for said spring and swingably arranged in said bore and a cam on said disc cooperating with a projection provided on said trigger. 100

3. A primer lock as set forth in the preceding claims, in which said cam disc is formed as a double armed lever one arm of which, during rotation of said cocking shaft for the purpose of cocking said percussion hammer, presses upon said trigger and the other arm of which, during the automatic return of the cocking shaft after release of the trigger and advance of the percussion bolt, presses against a stop of said percussion hammer for retracting said latter into a safety position, whereupon said cam disc occupies a position in front of said trigger and said stop of said percussion hammer. 115

In testimony whereof I have affixed my signature.
